CLOTHES HANGER

Chester H. MacSpadden, Ephrata, Wash.

Application July 5, 1950, Serial No. 172,137

1 Claim. (Cl. 223—88)

1

This invention relates to clothes hangers and more particularly to attachments applicable to an existing wire clothes hanger to provide pads or guards for the shoulder portions of a garment supported on the hanger to maintain garments against creasing or being pulled out of shape while supported on the hanger.

It is among the objects of the invention to provide improved clothes hanger attachments mountable on an ordinary wire hanger to constitute guards or pads for supporting the shoulder portions of garments mounted on the hanger in a smooth and uncreased condition, which attachments are easily mountable on and separable from an ordinary wire hanger, which are of simple and durable one piece construction and are economical to manufacture from suitable moldable material, and which are neat and attractive in appearance and effective in use.

Other objects and advantages will become apparent from a consideration of the following description and the appended claim in conjunction with the accompanying drawing wherein:

Figure 1 is a side elevational view of a fragmentary portion of a clothes hanger illustrative of the invention;

Figure 2 is a top plan view of the clothes hanger portion illustrated in Figure 1;

Figure 3 is a fragmentary cross sectional view on an enlarged scale on the line 3—3 of Figure 1;

Figure 4 is a fragmentary cross sectional view on an enlarged scale on the line 4—4 of Figure 1;

Figure 5 is a cross sectional view on an enlarged scale on the line 5—5 of Figure 1;

Figure 6 is a bottom plan view of the hanger portion illustrated in Figures 1 and 2; and

Figure 7 is a fragmentary bottom plan view with parts broken away and shown in cross section to better illustrate the construction of the device.

With continued reference to the drawing, the coat hanger of the present invention comprises, in general, an ordinary wire frame hanger 10 and two attachments, one of which is designated at 11. As the two attachments are identical in construction, it has been considered sufficient for the purposes of the present disclosure to illustrate one only of the attachments, the complementary attachment having been omitted for the purpose of simplifying the illustration.

The wire hanger 10 has a substantially straight bar 12 and two shoulder bars 13 and 14 joined at their outer ends to the respectively opposite

2

ends of the straight bar 12 and interconnected at their inner ends by a twist or wrap 15, one of the shoulder bars being extended past the wrap 15 and curved to provide a hook formation 16. The two shoulder bars 13 and 14 extend along the straight bar 12 from the ends to substantially the mid-length location of the latter and are spaced from and inclined away from the straight bar from the ends of the straight bar 10 toward the mid-length location.

As wire frame hangers of the character indicated are well known to the art, a more detailed description is considered unnecessary for the purposes of the present disclosure.

The attachment 11 comprises a flat plate portion 17 which is tapered in width substantially from one end to the other and is transversely curved to provide an upper convex and an under concave surface. The side edges of this plate are longitudinally curved and the ends of the plate are also curved and joined to the side edges to provide a continuous curve entirely around the plate.

Two oppositely disposed hook formations 18 and 19 are provided on the concave under surface of the plate near the smaller end of the tapered plate and receive one of the shoulder bars, for example, the shoulder bar 13, of the wire hanger therein. These hook formations 18 and 19 are spaced apart longitudinally of the plate and are offset relative to the longitudinal center line of the plate so that the shoulder bar of the hanger engaged therein will be biased to a position at which it is inclined relative to the longitudinal center line of the plate.

A single hook formation 20 wider than either of the hook formations 18 and 19 is provided on the concave under surface of the plate near the wider end of the latter and is joined to the plate at a location adjacent the longitudinal center line of the plate when the hanger shoulder bar is engaged therein.

A pair of spaced apart and substantially parallel tongues 21 and 22 project from the hook 20 at the side of the hook remote from the plate 17 and are positioned substantially radially of the transverse curvature of the plate. These tongues have a length such that when the hook 20 engages a shoulder bar of the hanger 10 near the outer end of such a shoulder bar, the distal ends of the tongues 21 and 22 will engage the straight bar 12 of the hanger near the corresponding end of the latter and hold the attachment against turning on the shoulder bar of the hanger. The hook 20 engages the curved por-

tion 23 of the shoulder bar at the corresponding end of the straight bar 12 and holds the attachment against sliding outwardly along the shoulder bar while the tongues 21 and 22 support the attachment against turning on the shoulder bar. The edge of each of the tongues 21 and 22 provides a continuous curve and the tongues taper in width in a direction away from the associated hook 20, as is clearly illustrated in Figure 1.

The bias between the plate and the corresponding shoulder bar imparted by the slightly offset portions of the hooks 18 and 19 relative to the longitudinal center line of the plate holds the tongues firmly in engagement with the bar 12 and the corresponding end portion of the shoulder bar 13.

The attachments may be formed of a suitable moldable material, such as synthetic resin plastic, hard rubber or metal, and are easily attached to and removed from the associated wire frame hanger.

Each attachment has a length materially less than the hanger shoulder bar to which it is to be attached and has a width only sufficient to support the shoulder portions of a garment in a smooth and uncreased condition. In mounting an attachment on a hanger the attachment is held substantially perpendicular to the shoulder bar of the hanger near the end of the shoulder bar remote from the hook formation 16 and adjacent the corresponding end portion 23, and the shoulder bar is inserted between the two hooks 18 and 19. The attachment is then turned through an angle of approximately 90 degrees so that the attachment projects outwardly of the adjacent end of the hanger. The attachment is then slid along the shoulder bar toward the hook formation 16 until the end of the attachment remote from the hook formation is disposed inwardly of the corresponding end portion 23 of the hanger. The shoulder bar 13 is then engaged in the hook 20 of the attachment and the attachment moved along the shoulder bar away from the hook formation 16, care being taken to hold the attachment in position such that the straight bar 12 of the hanger will enter the space between the tongues 21 and 22. Movement of the attachment in the same direction along the shoulder bar is continued until the hook 20 comes into engagement with the curved portion 23 at the outer end of the shoulder bar and the straight bar 12 and end portion 23 are both received between the distal end portions of the two tongues 21 and 22. The attachment is then firmly mounted on the hanger against unintentional movement or displacement.

In order to remove the attachment from the hanger the attachment is merely slid along the

corresponding shoulder bar toward the hook formation 16, the hook 20 is disengaged, and the attachment is then turned until the shoulder bar is disengaged from the hooks 18 and 19 and disposed in the space between these two hooks, whereupon the attachment may be moved away from the shoulder bar of the wire frame hanger.

Two similar attachments are required for each hanger, one attachment being mounted on each of the hanger shoulder bars 13 and 14 to properly support both of the shoulder portions of a garment hung on the hanger.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

A garment hanger attachment for supporting a garment shoulder comprising an elongated plate transversely curved and tapering in width from one end to the other, a pair of hook formations projecting from the concave surface of said plate near said other end and at locations spaced apart along the longitudinal center line of the plate, said hook formations facing in respectively opposite directions transversely of said plate and adapted to receive a shoulder bar of a wire garment hanger therein, a third hook formation projecting from the concave side of said plate near the mid-width location and adjacent said one end thereof and adapted to receive a clothes hanger shoulder bar received in said pair of hook formations, said third hook formation facing transversely of said plate in a direction opposite the adjacent hook formation of said pair of hook formations, and a pair of tongues projecting outwardly of the concave side of said plate from said third hook formation and spaced apart to receive an end portion of an associated garment hanger therebetween to support the attachment in operative position on a garment hanger.
